UNITED STATES PATENT OFFICE.

ELMER F. BLISS, OF SCHENECTADY, NEW YORK, ASSIGNOR TO GENERAL ELECTRIC COMPANY, A CORPORATION OF NEW YORK.

TARGET-SIGNAL.

No. 924,727.

Specification of Letters Patent. Patented June 15, 1908.

Application filed July 15, 1908. Serial No. 443,602.

To all whom it may concern:

Be it known that I, ELMER F. BLISS, a citizen of the United States, residing at Schenectady, county of Schenectady, State of New York, have invented certain new and useful Improvements in Target-Signals, of which the following is a specification.

My invention relates to signals of the disk or target type, in which a target in the form 10 of a thin disk is mounted on a central axis, and is rotated through ninety degrees to display or conceal it.

The object of my invention is to provide what may be termed a "three-position" signal of this type. For giving three distinctive indications, it has ordinarily been the practice heretofore to employ a pair of separate target signals displayed in different positions. By my invention all three indications are obtained at the same point, with a simple and compact arrangement of apparatus. I accomplish this result by providing a pair of unlike targets pivotally mounted on their central axes, with their axes in alinement, and means for rocking each target on its axis through ninety degrees independently of the other; at least, one of the targets being cut away along its axis, and overhanging the other, so that either target may be 30 displayed in substantially the same position.

My invention will best be understood by reference to the accompanying drawings, in which—

Figure 1 shows both front and side elevations of a target signal arranged in accordance with my invention, with both targets concealed; Fig. 2 shows similar views with one target displayed; Fig. 3 shows similar views with the other target displayed; and 40 Fig. 4 shows a perspective view of the two targets, separated from each other, so as more clearly to show their construction.

In the drawings A and A' represent two disks or targets pivoted on their central axes, 45 with their axes in alinement, and each target cut away along its axis, and overhanging the axis of the other, as is most clearly shown in Fig. 4. The targets are unlike in appearance, being made of different shapes or different colors, or preferably both. For instance, the target A may be circular, as shown, and colored red for the danger indication, while target A' may be diamond-shape and colored green, to give a caution indication. Each 55 target is movable on its axis through ninety

degrees independently of the other. For rocking the targets, they are provided with short cranks *a* and *a'*, respectively, connected to the cores of a pair of operating magnets B B'. In Figs. 1, 2 and 3, I have indicated 60 by a dotted line C a window, behind which the targets are displayed.

With both magnets B and B' energized, both disks are concealed, as shown in Fig. 1. In this position each disk lies in a horizontal 65 plane, or more properly speaking, in two horizontal planes, for each disk has its parts on opposite sides of its axis offset in different parallel planes, so that the relative positions of the two targets are reversed on opposite 70 sides of their common axis. This offsetting of the parts of each target, together with the cutting away of each target along its axis where it overhangs the other, permits the movement of either target through, ninety 75 degrees without interference with the other target. If the magnet B' is deenergized, its core falls, rocking the target A' through ninety degrees, as shown in Fig. 2, and consequently displaying it behind the window C. 80 If magnet B' is energized, and magnet B is deenergized, then target A' is concealed, while target A is displayed, as shown in Fig. 3.

It will be understood that, in order to illustrate my invention clearly, I have shown it somewhat diagrammatically, and I do not desire to limit myself to the particular construction and arrangement of parts here shown, but aim in the appended claims to 90 cover all modifications which are within the scope of my invention.

What I claim as new and desire to secure by Letters Patent of the United States, is:

1. In a signal, a pair of unlike targets 95 pivotally mounted on their central axes and with their axes in alinement, and means for rocking each target on its axis through ninety degrees independently of the other, at least one of said targets being cut away along its axis and overhanging the other so that either target may be displayed in substantially the same position.

2. In a signal, a pair of unlike targets 105 pivotally mounted on their central axes and with their axes in alinement, means for rocking each target on its axis through ninety degrees independently of the other, at least one of said targets being cut away along its axis and overhanging the other so that either tar- 110

get may be displayed in substantially the same position, and a pair of electromagnets for actuating said rocking means.

3. In a signal, a pair of unlike targets 5 pivotally mounted on their central axes and with their axes in alinement and each overhanging the axis of the other, and means for rocking each target on its axis through ninety degrees independently of the other.

10 4. In a signal, a pair of unlike targets pivotally mounted on their central axes and with their axes in alinement and each overhanging the axis of the other, and a pair of electromagnets connected to said targets 15 respectively and adapted to rock said targets on their axes through ninety degrees, each target being movable independently of the other.

5. In a signal, a pair of unlike targets 20 pivotally mounted on their central axes and with their axes in alinement and each overhanging the axis of the other, and at least one target having its parts on opposite sides of

its axis offset in different parallel planes, so that the relative positions of the two targets 25 are reversed on opposite sides of their common axis.

6. In a signal, a pair of unlike targets pivotally mounted on their central axes and with their axes in alinement, means for rocking each target on its axis through ninety degrees independently of the other, at least one of said targets being cut away along its axis and overhanging the other so that either target may be displayed in substantially the 35 same position, and at least one target having its parts on opposite sides of its axis offset in different parallel planes, so that the relative positions of the two targets are reversed on opposite sides of their common axis. 40

In witness whereof, I have hereunto set my hand this 13th day of July, 1908.

ELMER F. BLISS.
